SHAVING BRUSH

Hyman R. Segal, New York, N. Y.

Application July 19, 1933, Serial No. 681,078

12 Claims. (Cl. 15—185)

The present invention has to do with improvements in a shaving brush assembly and more particularly is directed to a pivotally supported brush adapted to be selectively swung in position 5 for use and in a position for non use. The shaving brush assembly comprises a holder, an invertible or reversible brush, pivotally sustained thereby and a casing which is adapted to enclose the brush and which is disconnectably carried by 10 the holder. In the assembly of the character referred to and in the non use position of the brush, the bristles of the latter are disposed within the holder and are pointing downwardly permitting any moisture on the bristles to drain by gravity 15 and separate therefrom, thus facilitating drying of the bristles. The moisture or water separated from the bristles, according to the invention, is collected in a basin or trap at the bottom of the holder. It is therefore an object of the invention to provide a shaving brush the bristles of 20 which may be readily dried during the period of non use and thus preventing the impairment or deterioration of the bristles which generally takes place when the bristles are in a normally moist 25 environment.

The invention has for another object to provide a novel invertible and rotatable shaving brush comprising an annular channel to collect the drippings from the bristles when the latter 30 are in a position for lathering.

The invention has for another object the provision of a holder which serves as a handle for the brush when the bristles are disposed in a position for use and which also serves to receive 35 the bristles when inverted for drying.

The invention has for another object the provision of a tumbler or casing removably and frictionally connected to a holder which pivotally supports a bristle carrying member.

The invention has for another object the provision of a neat and attractive compact assembly 40 having tumbler means for concealing the bristle carrying member in its inverted non use position.

Further objects, advantages and features of 45 the invention will appear as the description herein progresses, reference being made to the accompanying drawing in which

Fig. 1 is a view in perspective of a shaving brush assembly according to the invention.

Fig. 2 is a perspective view of the brush in an 50 inverted or non use position.

Fig. 3 is a perspective view of the brush with the bristles set in position for use and its tumbler 55 removed therefrom shown in perspective and inverted.

Fig. 4 is a section on the line 4—4 of Fig. 1. Fig. 5 is a section on the line 5—5 of Fig. 4 and Fig. 6 is a fragmentary section of a modification.

The shaving brush assembly is generally denoted 10 and consists of three components, namely, a holder or handle 11, a brush or bristle carrying member 12, and a tumbler or closure 13.

The holder comprises a circular flat bottom base 14 having the spaced upstanding arms 15 and 16. The base and the spaced arms may be cast as a unitary embodiment of a suitable hard rubber, bakelite or made of ivory, bone or of any suitable attractive material or composition. The upper portions of the arms are substantially 60 parallel while other corresponding portions thereof diverge outwardly and downwardly, the inner surfaces of the tapering portions being preferably arcuately shaped. The inside face of the base or disc 14 is provided with a depression 17 which 65 serves as a trap or trough for collecting the particles of water dripping from the bristles 18 of the brush 12.

The brush or bristle carrying member 12 includes an octagonally shaped plug or socket 19 80 having a centrally disposed opening 20 in which inner ends of the bristles 18 are appropriately secured. The plug may be made, if desired, of any suitable composition, such as hard rubber, bakelite, bone, ivory, etc. The socket or brush 85 comprises an annular channel 21 for receiving the drippings from the bristles when the latter are in position for lathering. As shown the plug is of octagonal form but obviously other forms 90 may be employed.

According to the invention, the upper portions of the spaced arms pivotally support the body of the plug. For this purpose each of the arms fixedly carries an inwardly extending overhanging cylindrical pin or ferrule 21, the outer ends of 95 the pins being provided with an upset portion or flange 22 disposed in a counter-sunk part or recess 23, the inner ends of the pins project in opposed recesses 24 of the plug. Each of the pins is provided with a circular head or disc shaped member 25 against which one end of a helicoidal spring 26 abuts. The springs 26 encircle each end of the pins and also cooperate with a suitable perforated disc washer or bearing 27 fixedly disposed in each recess 24 to urge the upper ends of the arms against the sides of the plug. For purposes of the present specification pins as 21 may be considered as a part of the respective arms of the holder.

With the pins 21 journalled on the bearing members 27, the plug may be swung to a position as shown in Fig. 3 such that its bristles point upwardly and ready for use to lather or from such 5 position to an inverted position, that is, the bristles pointing downwardly and disposed between the spaced arms of the handle, as illustrated in Figs. 2, 4 and 6. In their inverted position, any particles of water, thereon, will flow 10 downwardly by gravity and will drain into and collect in the trough 17.

For holding the plug in a position for lathering or in an inverted position when not in use, each of the arms is provided with a relatively 15 elongated vertically disposed integral lug or rib 28 which are removably received in correspondingly shaped channels or vertically arranged grooves 29 on respective companion faces of the plug. In the use or non use position of the plug 20 the action of the springs 26 against heads 25 and associated bearing members 27 is such as to maintain the lugs or ribs 28 interlocked within their cooperating channels on the plug and thereby 25 preclude the latter from being accidentally displaced or tilted away from its vertical or interlocked positions.

Where, however, the plug is swung from a position for non use to a position for use or vice versa, the ribs 28 are disconnected from their 30 channels and movably embrace adjacent sides of the plug, causing the upper ends of the arms to slightly "give" or move outwardly due to the resiliency thereof. In this movement of the plug the springs 26 have a tendency to maintain the 35 ribs now out of their channels, against the sides of the plug. In reaching a vertical position, the channels 29 of the plug interlock with their respective ribs on the arms.

The tumbler or closure 13 comprises a circular 40 wall 30 from which depends an annular skirt 31 having its intermediate and lower portions slightly flared or tapering with the inside circular face of its rim 32 adapted to removably, frictionally and snugly embrace the lower or tapering outside 45 curved faces of the upstanding arms 15 and 16, the movement of the skirt 31, on the holder being limited by reason of the circular shoulder 33 on the base 14, it being noted, that the arms of the 50 holder are interconnected at their bottom by curved vertically disposed flanges 34 to increase the holding capacity of the trough 17, the outside faces of circular flanges 34 also cooperating to snugly and removably engage the inner curved face of the rim 32.

To facilitate the drying of the bristles in their 55 non use or inverted position after the tumbler or casing is secured to the handle of the brush, the tumbler is provided with a plurality of perforations 35 to permit currents of air to enter into and leave the bristle receiving chamber, namely 60 between the spaced arms of the holder.

In the non use position of the brush, the plug 65 has been inverted and the bristles are disposed between the spaced arms of the handle. The casing or housing 35 has also been inverted and placed over the arms and secured to the holder. This assembly is shown in Figs. 1 to 4 inclusive.

Where it is desired to use the brush for lathering, the housing is first removed from the holder 70 and the plug is rotatably swung one hundred and eighty degrees positioning the free ends of the bristles to be ready for use.

With the plug interlocked in position for use 75 and against tilting, the tumbler may be approxi-

priated to hold any suitable fluid for moistening the bristle preparatory to lathering.

In the form according to Fig. 6, which shows a slight variation of the earlier form of Figs. 1 to 5 inclusive, the arms 15 and 16 of the holder include inwardly extending pins 35 and 36 respectively which are pivotally disposed in recesses as 37, the pins 35 and 36 being urged inwardly and held within their recesses by reason of the inward pressure exerted by the resilient arms 15 and 16. As in the case of the form according to Figs. 1 to 5 inclusive, the plug 19 of Fig. 6 may be held interlocked in either lathering position or inverted non use position of the bristles by similar ribs 28 on the arms and cooperating channels 29 on the plug. If desired the arms of the embodiment shown in Fig. 6, may be disconnected from the plug by simply spreading the arms 15 and 16 apart to remove their pins 35 and 36 from their openings or recesses 37.

While certain preferred embodiments of the invention have been shown and described, it will be understood that changes in the form, arrangements, proportions, sizes and details thereof may be made without departing from the scope of the invention as defined in the appended claims.

Having described my invention, what I claim and desire to secure by Letters Patent is:—

1. In combination, a handle having a base and upstanding spaced arms integrally connected thereto, a reversible brush comprising a socket having bristles secured therein and projecting beyond thereof, said arms having means pivotally supporting said brush, the latter being adapted to be swung to position said bristles between said arms or above thereof, said base comprising a relatively wide trough for collecting liquid particles from said bristles when the latter are disposed between said arms, said brush having means for collecting liquid particles when said bristles are extended above said arms, and means for holding said socket against tilting when said bristles are disposed between the arms or above thereof.

2. In combination, a handle having a base and upstanding spaced arms integrally connected thereto, a reversible brush comprising a socket having bristles secured therein and projecting beyond thereof, said arms having inwardly extending pins pivotally supporting said brush, said brush being adapted to be swung to position the bristles thereof between or above said arms, said base comprising a relatively wide trough for collecting particles of liquid draining from said bristles when disposed between said arms, a rib carried by each arm, said brush having opposing sides straddled by said arms and each including a channel adapted to removably interlock with a companion rib of an associated arm.

3. In combination, a holder having a base and upstanding arms, pins carried by said arms, a reversible bristle carrying member comprising recesses adapted to receive said pins, a flange carried by each of said pins, a perforated washer fixedly mounted in each recess and adapted to pivotally support said pins, said member having opposing sides each of which includes a channel, said arms being adapted to straddle said opposing sides and each having a rib for interlocking with a channel of said member, and spring means mounted on said pins abutting said flanges and washers to maintain said ribs removably interlocked with said channels to prevent tilting of said brush relative to arms.

4. In combination, a holder having a base and

- upstanding arms integrally connected thereto, pins carried by said arms, a reversible bristle carrying member comprising recesses adapted to receive said pins, a flange carried by each of said pins, a perforated washer fixedly mounted in each recess and adapted to pivotally support said pins, said member having opposing sides each of which include a channel, said arms being adapted to straddle said opposing sides and each having a rib for interlocking with a channel of said member, and spring means mounted on said pins abutting said flanges and washers to maintain said ribs removably interlocked with said channels to prevent tilting of said brush relative to arms, 10 said base comprising a trough for collecting moisture from the bristles when the latter are disposed between said arms, the member having means for collecting moisture from said bristles when the latter are disposed above said arms.
- 20 5. A shaving brush, comprising, in combination a handle having a base, spaced and upstanding arms integrally connected to said base, a reversible plug comprising a socket having bristles secured therein, said arms having inwardly projecting fulcrum pins pivotally supporting said plug, the latter being adapted to be swung to position the bristles above said handle or between said arms, said base having a depression to provide a relatively wide trough for collecting particles of liquid draining from said bristles when the latter are disposed between said arms, a rib carried by each arm, said plug having oppositely disposed sides closely straddled by said arms and each including a channel adapted to removably interlock with a companion rib of an associated arm.
- 30 6. A shaving brush, comprising in combination, a handle having a base, spaced resilient arms connected to said base, a reversible plug comprising a socket having bristles secured therein, said arms having inwardly projecting fulcrum pins pivotally and removably supporting said plug, the latter being adapted to be swung to position said bristles above said handle or between said arms, said base having a trough for collecting particles of liquid draining from said bristles when the latter are disposed between said arms, a rib carried by each arm, said plug having oppositely disposed sides closely and removably straddled by said arms, each of said sides having a channel adapted to removably interlock with a companion rib of an associated arm.
- 40 7. A shaving brush, comprising, in combination, a handle having a base, spaced resilient arms integrally connected to said base, a reversible plug comprising a socket having bristles secured therein, said arms having inwardly projecting fulcrum pins pivotally supporting said plug and removably received thereby, the latter being adapted to be swung to be rotated to position said bristles above said handle or between said arms, said base having a relatively wide trough for collecting liquid particles draining from said bristles when the latter are disposed between said arms, a rib carried by each arm, said plug having oppositely disposed sides closely and removably straddled by said arms, each of said sides having a channel to removably interlock with a companion rib of an associated arm, said arms having upper portions adapted to be spread apart and bodily move said pins out-wardly to remove said fulcrum pins from said plug.
- 50 8. A shaving brush, comprising, in combination, a handle having a base providing a relatively wide trough, spaced upstanding resilient arms each having an inwardly extending rib and a pin integral therewith, a reversible plug comprising a socket having bristles secured therein, said plug having recesses for removably receiving said pins to provide a connection for pivotally supporting said plug, the plug having channels to removably interlock with said ribs to prevent tilting of said plug, said arms normally exerting an inwardly directed pressure against said plug to prevent removal of said pins from said recesses.
- 60 9. A shaving brush, comprising, in combination, a handle having a base providing a relatively wide trough, spaced upstanding resilient arms each having an inwardly extending rib and fulcrum pin integral therewith, a reversible and rotatable plug comprising a socket having bristles secured therein and projecting beyond thereof, said plug having recesses for removably receiving said pins to provide a connection for pivotally and removably supporting said plug, the latter having means to removably interlock with said ribs to prevent tilting of said plug, said ribs normally abutting said plug when the latter is rotated.
- 70 10. A shaving brush, comprising, in combination, a handle having a base and upstanding spaced resilient arms, a removable brush comprising a socket having bristles secured therein and projecting beyond thereof, said arms having means pivotally and removably supporting said brush, the latter being adapted to be swung to position said bristles between said arms or above thereof, said base comprising a relatively wide trough for collecting particles of liquid draining from said bristles when the latter are disposed between said arms, and interlocking means for removably holding said socket against tilting when said bristles are disposed between the arms or above thereof.
- 80 11. A shaving brush, comprising, in combination, a handle having a base and upstanding spaced resilient arms, a removable and reversible brush comprising a socket having bristles secured therein and projecting beyond thereof, said arms having fulcrum means integral therewith for pivotally and disconnectably supporting said brush, said arms normally abutting opposing sides of said socket and adapted to be diverged for disconnecting said fulcrum means from said brush.
- 90 12. A shaving brush, comprising, in combination, a handle having a base providing a relatively wide trough, resilient arms projecting upwardly from said base, a removable and reversible brush comprising a socket having bristles secured therein and projecting beyond thereof, said arms having fulcrum means integral therewith and overhanging the same, said brush having means to receive said fulcrum means to provide a pivotal connection, said arms and brush comprising cooperating interlocking means to prevent tilting of said brush, said arms being adapted to be diverged to remove said fulcrum means from said brush for disabling said pivotal connection.
